(57) **CLAIM**

(21) Appl. No.: **29/304,401**

The ornamental design for a latch assembly with release lever, as shown and described.

(22) Filed: **Feb. 29, 2008**

DESCRIPTION

(51) **LOC (9) Cl.** **08-07**

FIG. 1 is a top-front perspective view of a latch assembly with release lever showing our new design;

(52) **U.S. Cl.** **D8/331; D8/336**

FIG. 2 is a side view of the latch assembly with release lever depicted in FIG. 1;

(58) **Field of Classification Search** D8/330,
D8/331, 336–339, 343; 70/141, 51, 99, 195;

FIG. 3 is a front view of the latch assembly with release lever depicted in FIGS. 1–2;

292/308, 359, DIG. 30

FIG. 4 is a top-rear perspective view of the latch assembly with release lever depicted in FIGS. 1–3;

See application file for complete search history.

FIG. 5 is a top view of the latch assembly with release lever depicted in FIGS. 1–4;

(56) **References Cited**

FIG. 6 is a rear view of the latch assembly with release lever depicted in FIGS. 1–5.

U.S. PATENT DOCUMENTS

FIG. 7 is bottom view of the latch assembly with release lever depicted in FIGS. 1–6; and,
